CAR CONSTRUCTION

Nathaniel S. Reeder, New York, N. Y., assignor to
 Pressed Steel Car Company, Pittsburgh, Pa., a
 corporation of New Jersey

Application May 1, 1936, Serial No. 77,342

5 Claims. (Cl. 105—290)

This invention relates to vehicles employed in collecting and transporting lading. The particular embodiment of the invention is disclosed in the drawing as applied to an open top railroad car employed in transporting refuse from collecting stations to a place of disposal.

Prior existing railroad cars used for this purpose often presented serious difficulties in unloading the refuse. As the cars are loaded at 10 different collecting stations within the metropolitan area and then hauled to a nearby dumping ground, the refuse forming the lading often comprises a mixture of discarded articles of food, household articles, waste products and the various 15 other types of rubbish accumulated in daily city life. The character of the lading within the car makes the discharge thereof through the ordinary discharge openings in the floor of standard railroad cars impractical since the discharge 20 openings are either clogged or obstructed, or the lading forms an arch over the opening preventing further discharge. The lading could be readily discharged from open top cars in a car dumper, which inverts the car, but such a means is seldom 25 available or is unsuitable because of its size and expense.

Heretofore, efforts to overcome the foregoing objections have resulted in the building of cars having the entire side of the car hinged adjacent 30 the floor or the upper edge of the side of the car. Such a construction requires some extraneous mechanical means for raising and lowering the heavy car sides forming the doors and makes this 35 design of car objectionable. When the car sides are hinged adjacent the floor of the body and opened outwardly and downwardly to discharge the lading, the lading lodges on the door, preventing complete discharge of the lading and necessitating additional labor through a second 40 handling of the material to remove it from the door. Other objections arise because of the necessary increase in weight due to the strengthening of the hinged sides to withstand handling.

The present invention overcomes these and 45 other prior objectionable features by a novel manner of constructing the side wall of the car as a pair of opposing doors, one door of the pair opening upward and the other opening downward in the discharge of the lading, the meeting 50 edge of the doors being along a line disposed longitudinally of the car and intermediate the vertical extremities of the side of the car. For 55 this type of car a simple and efficient mechanical means may be mounted on the ends of the cars for opening the doors with a minimum of man-

ual effort. This method of mounting the doors has many advantages and greatly reduces the manual effort required in operating the doors by connecting both doors at one side of the car to the same operating mechanism so that the force 5 of gravity and the lading acting upon the lower door assists in lifting the upper door into open position and the force of gravity acting on the upper door assists in moving the lower door into closed position.

One object of the present invention is to provide 10 a railroad car with body side walls which are readily positioned to effect a complete and rapid discharge of the lading.

Another object of the invention is to provide, 15 as an integral part of the car, a manually operable mechanism for handling said car side walls.

Another object of the invention is to provide 20 such mechanism for the purpose as will utilize the weight of the doors forming the car side walls 25 to reduce the manual effort required to operate the mechanism.

Another object of the invention is to provide 30 a car of the character described with body side walls formed of doors having their meeting edge 25 disposed longitudinally of the car intermediate the upper and lower limits of the side of the car body and the lower door hinged adjacent the floor of the car body in such a manner as to afford an unobstructed discharge opening at the level with 35 the car floor and extending substantially the full length of the car body.

A further object of the invention is to provide 40 a car side wall with doors of the character described, the lower door being of such a size as to 35 form an apron to discharge the lading away from the car and tracks, and yet not of such width as to provide a lodging place for the lading and prevent the discharge thereof.

In the drawings forming part of this specification, the inventive concept has been broadly disclosed and one specific embodiment of the manually operable mechanism for handling the doors, it being understood that many changes 45 may be made in the specific details without departing from the invention hereinafter described in which Fig. 1 of the drawing discloses a side elevation of an open top car equipped with the invention; Fig. 2 is an enlarged transverse section taken on the lines 2—2 of Fig. 1 with the door 50 shown in open position; Fig. 3 is a further enlarged section taken on the lines 3—3 of Fig. 2 showing a detail of the door operating mechanism; Figs. 4 and 5 are enlarged sections taken 55 on lines 4—4 and 5—5 of Figs. 1 and 2 respective- 55

ly showing respectively details of the door and method of mounting the mechanism on the car.

Referring now to the drawing where like reference characters refer to like parts, reference character 1 indicates a railroad car of the usual construction comprising side and end walls, a floor, and wheeled trucks beneath opposite ends of the car. The end walls 2 of the car preferably extend from side sill 3 to side sill 3 of the car and 10 extend from the car floor 4 to the top end rail 5 of the car. These end walls 2 are preferably disposed inwardly from the ends of the car and a platform 6 on the underframe of the car extends from each end wall outwardly to the ends 15 of the car. Side ladders 7 and 7^a are disposed at opposite ends of the car for the convenience of trainmen and to assist the operators of the car in mounting to the platforms 6. The side walls of the car are preferably formed of side 20 posts 34, side plate 9, top rail 9^a, an upper door 8 hinged at 8^a to the side plate 9 of the car and a lower side door 10 hinged at 10^a adjacent the floor of the car. The doors 8 and 10 are of sufficient width to meet intermediate the vertical limits of 25 the car side wall and have their meeting edges reinforced by overlapping members 11 and 12, the member 12 secured to the door 10 overlying the member 11 secured to the door 8 so as to prevent leakage of any fluid mixed with the lading. The 30 bottom edge of the bottom door 10 preferably forms a water-tight seal with the floor of the car by any well-known method.

The car body as thus described comprises a closed lading retaining receptacle having an open 35 top through which the lading may be placed within the car and opposite side walls formed of doors opening outwardly for the discharge of the lading to either or both sides of the car. The side doors of the car may be secured in position by any 40 desirable method known to the art and the doors may be opened and closed in any desirable manner. I prefer to mount on the end of the car, above the platform 6, a manually operable mechanism for opening and closing the doors so that 45 the operator may stand on the platform 6 whilst manipulating the mechanism as hereinafter described.

One form of mechanism for operating the doors, as shown in Figs. 2 to 4 inclusive of the drawing, comprises a track disposed transversely of and in spaced relation to the car end wall 2 above the platform 6 and secured at opposite sides of the car by means of brackets 13. The track comprises an upper member 14 having a 50 rack 15 secured thereto and preferably disposed beneath the member 14, and a lower member 16. The members 14 and 16 are disposed in vertical spaced relation having mounted thereon a carriage 17 preferably comprising outer side walls 17^a and inner side walls 17^b having their upper edges joined by a U-shaped member 18^a and their lower edges joined by the inverted U-shaped member 18^b. Disposed between the members 17^a and 17^b is a gear wheel 19 mounted on a shaft 20 55 journaled in the members 17^a and 17^b and extending beyond the member 17^a to receive an operating wheel 21. Shaft 20 has two concentric bearings 37 and 38 at each side of gear 19, the outer bearing 38 rolling on track member 16 to 60 support the carriage 17, the inner bearing 37 supporting the shaft 20 during rotation of gear 19 as hereinafter described. In this manner the carriage 17 has a rolling instead of a sliding movement on track member 16. The gear 19 is in 65 engagement with the rack 15 disposed below the

member 14 and the member 16 is preferably of U-shape to receive the underside of the gear 19. Pivotally mounted on the member 18^a by means of the pin 22 is a door lever 23 having its outer end pivotally mounted by means of the pin 24 in 5 a bracket 25 secured to the door 8 and pivotally mounted on the member 18^b of the carriage by means of the pin 26 is the door lever 27, having its free end pivotally connected to the door 10 by means of the pin 28 journaled in the bracket 29 10 secured to the door.

These door mechanisms are mounted at each side of each end of the car and two door mechanisms preferably connected to each pair of side doors so that the doors at each side of the car 15 may be independently operated by men standing at opposite ends of the car. The inward movement of the carriage 17 is limited by a stop 30 secured to each end wall and having a portion 31 extending between the members 14 and 16 of 20 the track to engage an edge of the carriage 17, it being understood that the track is spaced outwardly from the end wall as shown in Fig. 5 and the end wall is braced by means of the longitudinally disposed member 32. The side doors are 25 preferably locked in closed position independently of the operating mechanism. Any form of lock suitable for the purpose may be used, one form being shown in Fig. 5 comprising a member 33 secured to the corner post 34 by means of the 30 backing plate 35 and extending through openings in the car side wall doors. The member 33 has an opening adjacent its outer end to receive the wedge 36, locking the doors in closed position.

Due to the character of the lading it is not 35 desirable to manually handle the same and a preferred form of discharging the lading is to open the side doors and direct a stream of water under pressure against the lading, washing it from the car. This stream of water may be directed against the lading from either or both 40 sides of the car, washing the lading from the floor 4, outwardly over the bottom doors 10. In this manner the cars are not only unloaded but are kept clean, avoiding any offensive odors resulting from decayed vegetable and animal matter which might cling to the car.

The operation of the doors is as follows: after the car has arrived at the place of discharge, the wedges 36 are removed and operators standing 50 on the platform 6 at opposite ends of the car grasp the operating wheels 21 of the mechanisms secured to the doors at one side of the car, turning the wheel towards the opposite side of the car. The gear 19 cooperating with the rack 15 55 on the member 14 of the track moves the carriage 17 and attached arms 23 and 27 outwardly towards the side of the car. The arms 23 and 27 pivoting on their connections to the carriage 17, swing the doors 8 and 10 outwardly on their 60 hinge connections to the car. When the doors are in fully opened position they will remain in this position until closed. The operating wheel 21 on the opposite side of the car is similarly operated to open the doors 8 and 10 on the opposite side of the car, after which the streams of water are directed against the lading as previously described.

During the opening of the doors, the weight of the lading pressing against the door 10 and the 70 weight of the door 10 tends to pull the carriage 17 outwardly towards the side of the car and assist in raising the upper door 8. Similarly, during the closing movements of the door, the weight of the door 8 acts through its lever 23 75

on the carriage 17 and assists in closing the bottom door 10.

Whilst no details of construction of the car body and doors have been illustrated in the drawing, brackets 25 and 29 have been shown extending longitudinally of the doors to reinforce same and it is to be understood that any suitable reinforcing may be attached to the doors as may be found necessary.

10 Many obvious modifications of the invention will suggest themselves to those skilled in the art and I do not wish to limit myself by any details of construction except as hereinafter set forth in the appended claims.

15 Having thus described the invention what I claim as new and desire to secure by Letters Patent is:

1. In a railway car having a floor, body side and end walls forming therewith a lading enclosure with one side wall thereof including a pair of doors extending longitudinally of the side wall with their adjacent meeting edges disposed above the floor and their opposite edges hinged adjacent the upper and lower portions of the side wall to open outwardly for discharge of lading, a door operating mechanism at each end of said pair of doors including a track comprising vertically spaced members disposed transversely of each end wall, the upper of said track members 20 having a rack on the lower face thereof, the lower of said track members being U-shaped with the arms of the U extending towards the rack, a carriage mounted on said track and including a rotatably mounted gear engaging the rack of said 25 upper track member and extending between the arms of the lower track member, a shaft upon which said gear is mounted, annular bearings on said shaft on opposite sides of said gear and a second annular bearing enclosing said first-named bearing on opposite sides of the gear and 30 engaging the upper face of the arms of the U-shaped track member to support the carriage, said annular bearings on each side of the said gear being rotatable relative to each other, link 35 connections between each carriage member and the adjacent end of the upper and lower door of the side wall, and means for rotating said gear of each said carriage in engagement with said rack to move said carriage longitudinally of the track for actuating the associated doors.

40 2. In a railway car having a side wall including a pair of opposing doors extending from end wall to end wall of the car, a door operating mechanism comprising track means on each end wall and extending inwardly from said side wall, carriage means supported by each said track for

movement longitudinally of said track, means on said carriage engaging said track, independently of the supporting engagement therewith, to selectively move the carriage upon the track, and an arm pivoted to each end of each door and a 5 pivotal connection between each door arm and the adjacent carriage.

3. In a railway car having a side wall including a pair of opposing doors extending from end wall to end wall of the car, a door operating mechanism comprising a track extending inwardly of each end wall from each end of said pair of doors and comprising upper and lower members, a carriage mounted on each said track and comprising side walls disposed on opposite sides of said track, 10 end walls connecting said side walls exteriorly of said track and propelling means disposed between said track members and journaled in said side members, and door arms pivotally connected to the adjacent ends of the doors and to said 15 carriage.

4. In a railway car having end walls and opposite side walls, each of the latter including a pair of opposing doors extending between said end walls, a door operating mechanism comprising 20 a track on each end wall and extending between the side walls, each track including a bottom member having a recess in the top face thereof and a top member spaced from the bottom member and including a rack overlying said recess 25 of the bottom member, an arm pivoted to each end of each door and extending inwardly of the car towards said tracks, a carriage member on each track adjacent each end of each pair of doors and pivotally connecting the inner ends 30 of said arms of the respective pair of doors, a gear mounted on a shaft journaled on each carriage and engaging the rack on the top track member, said gear extending into the recess of the bottom member and the shaft thereof being 35 supported on said bottom track member, and means for rotating said shaft to move said carriage upon said track for actuating the associated 40 side doors of the car.

5. In a door operating mechanism of the character described, the combination of a track, a carriage, mutually engaging means on said track and carriage for selectively moving the carriage in opposite directions upon the track, a bearing on the carriage supporting said carriage-carried 45 means, and a second bearing associated with the first-named bearing, said second bearing engaging the track to support the carriage thereupon and engaging the first-named bearing to rotatably support same upon the carriage.

NATHANIEL S. REEDER.
